ABSTRACT

A device is disclosed for plumbing a vertical spindle on a textile machine wherein the machine has a rail that traverses up and down to distribute yarn along the

length of a textile yarn carrier that resides around the spindle during normal operation. The device includes an elongated cylindrical member having a longitudinal bore therein that snugly fits about a spindle. A collar is positioned around the cylindrical member and is vertically adjustable therealong. The collar has initial spindle adjustment means such as one or more pins depending downwardly therefrom, whereby once the device is positioned over a loosened spindle, the pin engages a traverse rail ring that surrounds the spindle and automatically biases the spindle into approximate plumb (a condition perpendicular to the traverse rail and in the center of the ring) to within a few thousandths of an inch. An adjustable indicator is also provided that can be moved up and down the length of the spindle and can be rotated around the spindle to indicate a particular position where the spindle is out of plumb and also the magnitude of deviation. The device may also be equipped with an internal bearing surface which permits use of the device on a rotating spindle. Furthermore, the device may optionally include a spirit level positioned in the top of the cylindrical member and also an extensible stop to prevent the device from rotating with the spindle.

SPINDLE PLUMBING DEVICE

BACKGROUND OF THE INVENTION

During spinning, twisting, or otherwise handling of a textile yarn, yarn is uniformly deposited around a yarn carrier received on a rotating spindle. It is quite important that the spindle be properly positioned to enable placement of the yarn on the carrier as desired to produce a predetermined shape for the yarn package, to prevent the yarn from being frayed and the like. As the spindle rotates, a ring surrounding the spindle traverses a predetermined length of the spindle, being carried by a traverse rail. Yarn thus passes through a yarn traveler that travels around the ring and is deposited onto a portion of the carrier adjacent the ring. The spindle should thus be plumb (perpendicular to the traverse rail and centrally located within the ring surrounding same).

Historically, spindle plumbing has required a considerable amount of time and effort. Labor costs have been high and the machines have been held out of production for long periods of time. Such plumbing has generally been conducted by loosening the spindle at a point beneath a spindle support rail and adjusting the spindle by trial and error, using eyesight to determine proper spindle location. Additionally, spirit levels, plastics discs, and the like have been used, but without the realization of any real improvement, either in time or accuracy. The individual would thus use an available device, if any, and determine by eyesight whether the spindle was properly centered in the ring and thus perpendicular to the traverse rail. Such spindle plumbing has led to problems. A spindle that is out of plumb by only a few thousandths of an inch can cause the building of an improper yarn package and/or the manufacture of second quality yarn due to abrasion of the yarn from contact with the traverse rail. This frayed yarn is not visible to the naked eye and does not show up until woven into a fabric and the fabric dyed or finished.

Once a spindle was adjusted to the proper position, if necessary, precision paper was used to wedge or shim the spindle in this position, after which the spindle was then tightened against the spindle support rail, and the machine returned to operation. Heretofore, spindles have been plumbed idle. Since the plumb of the spindle can change when the spindle rotates, and since the rotating spindle is more nearly at actual conditions, plumbing of the idle spindle is not an optimum operation. There has been no means before now, however, for plumbing a spindle while the spindle is rotating.

The device manufactured according to the teachings of the present invention can now be used to overcome the disadvantages of the prior art. Not only can a spindle now be plumbed while idle and while rotating, but also a precision instrument is available to remove the majority of the human error due to inaccurate sighting of the device. Moreover, whereas, it has been previously necessary to strike the spindle with a hammer or other suitable tool to initially approach a plumb position, the device of the present invention automatically forces the spindle into approximate plumb, within a few thousandths of an inch, after which a precision indicator may be used to finalize plumbing of the spindle. Use of the device according to the teachings of the present invention thus reduces the time required to plumb a spindle, permits better plumbing accuracy, and enables

the manufacture of a proper yarn package while reducing the production of second quality yarn.

The prior art is deficient in teaching or suggesting the device of the present invention. Exemplary of the prior art are U. S. Pat. Nos. 686,975 to Kelly; 2,240,337 to Lannen; 2,356,311 to Geier and 2,856,696 to Williams.

SUMMARY OF THE INVENTION

It is an object of the present invention to provide a device for plumbing a vertical spindle on a textile machine.

A further object of the present invention is to provide an improved device for plumbing a rotating vertical spindle on a textile machine.

Still further, another object of the present invention is to provide an improved device for precisely adjusting a vertical spindle on a textile machine without the necessity of a trial and error eyesight evaluation of the position of the spindle.

Generally speaking, the device of the present invention comprises an elongated cylindrical member having a longitudinal bore therein, said member being adapted to reside over a vertical spindle, a vertically adjustable collar received around said elongated member, said collar having an initial spindle adjustment means thereon for engagement with a ring surrounding said spindle; and an adjustable indicator means associated with said elongated member for vertical and horizontal adjustment with respect thereto, said indicator means being movable around said spindle to determine whether said spindle is perpendicular to said rail and located in the center of said ring.

More specifically, the basic device of the present invention includes an elongated member having a longitudinal bore therein that snugly fits around a spindle. An adjustable collar having at least one pin type member extending outwardly therefrom in an axial manner engages the ring of the traverse rail which forces the loosened spindle to move towards the center of the ring as the collar is rotated around the ring. Depending upon the particular accuracy and placement of the pin type member, the spindle can be brought within a small number of thousandths of an inch of accurate plumb. Thereafter, the adjustable indicator means having a feeler member for engagement with said ring may be moved along the length of the spindle to the desired position as is indicated by the particular placement of the rail and can be rotated around the rail. As the indicator is moved around the ring, a feeler riding on the ring will indicate any position in which the spindle is out of plumb, the magnitude of deviation and the direction. After detecting such a condition, the spindle can be tapped very lightly in the appropriate direction until accurate adjustment is realized.

As mentioned earlier, a device manufactured according to the present invention may be successfully used to plumb a spindle while the spindle is rotating. A bearing surface is placed within the longitudinal bore of the elongated member and secured therein. The spindle then fits snugly within a central tubular member or rail of the bearing which is provided with roller members. The spindle and tubular member can thus rotate while the remainder of the device is held against rotation. An adjustable stop received on the elongated member engages the next adjacent spindle and

prevents the device from rotating along with the rotating spindle being plumbed. The spindle can now be plumbed while rotating, by use of the device as explained herein. Optionally, the collar or collars received around the elongated member can have bearings thereon to permit independent rotation of the collars with respect to the elongated cylindrical member. Hence with the spindle rotating and the elongated member being held against rotation by the stop means, the collars may be independently rotated around the elongated member to plumb the spindle.

A further feature of the present invention is the optional addition of a spirit level at the top of the elongated member. This feature has per se, been presented in the prior art. The level addition to the device of the present invention, however, is not the primary adjustment means, but is used merely as a means to quickly check accuracy of the spindle plumbing accomplished by the initial adjustment means and the indicator. The spirit level may be used on any embodiment of a device according to the teachings of the present invention.

BRIEF DESCRIPTION OF THE DRAWINGS

FIG. 1 is a vertical cross sectional view of a spindle plumbing device according to the teachings of the present invention shown in use around a vertical spindle of a textile machine with only a portion of a spindle support rail and traverse rail being shown.

FIG. 2 is a top view of a spindle plumbing device according to the teachings of the present invention as shown in FIG. 1.

FIG. 3 is a cross sectional view of a further embodiment of the spindle plumbing device according to the teachings of the present invention.

FIG. 4 is an end view of the elongated member of a device according to the teachings of the present invention showing a bearing surface received therein.

FIG. 5 is a top view of an elongated cylindrical member of a device according to the teachings of the present invention showing a spirit level positioned thereon.

DESCRIPTION OF THE PREFERRED EMBODIMENTS

Referring to the Figures of the drawings, the preferred specific embodiments of the present invention will now be described in detail. In FIG. 1, there is shown a portion of a textile machine such as a spinning machine, twister or the like having a spindle support rail 10 on which is rotatably supported a spindle generally indicated as 20 and a traverse rail 30 that normally traverses up and down a predetermined length of spindle 20 permitting yarn to be placed on a textile carrier (not shown) that is received on spindle 20. A textile machine such as the type being discussed would normally have a large number of such spindles extending along the length thereof. A ring 32 is shown on traverse rail 30 and surrounding a body 22 of spindle 20. Yarn thus passes through a traveler (not shown) that is received on and rotates around ring 32, and is deposited onto a textile carrier. It is quite desirable to produce a yarn package as uniform as possible and also to provide yarn that has not been adversely affected. In so doing, the vertical spindle should be as close to perpendicular as possible with respect to traverse rail 30

and also should be positioned in the precise center of ring 32 which surrounds spindle 20. Spindle 20 is generally rotatably supported by a spindle support assembly generally indicated as 15 which secures spindle 20 to rail 10 at the proper attitude when tightened thereagainst by one or more of nuts 16, 17 and 18. A whorl 19 is also provided at the base of spindle 20 to provide high speed rotation thereto by the passage of a belt or the like (not shown) therearound.

On a periodic basis, it is necessary for the spindles being used on the textile machine to be adjusted as described above. At such time, the spindle support assembly 15 is slightly loosened from rail 10 and the spindle 20 can now be adjusted. After adjustment, spindle support assembly 15 is again tightened against rail 10 to maintain the new adjustment.

The device of the present invention is used to adjust the loosened spindle 20 and comprises an elongated cylindrical member 40 having a concentric longitudinal bore 41 extending therein. In the embodiment shown in FIG. 1, the spindle body 22 is illustrated extending upwardly into bore 41 of elongated cylindrical member 40 and residing snugly therein. An adjustable collar or clamp 42 is provided around cylindrical member 40 and held thereon by a bolt 43 or other suitable locking means so as to permit collar 42 to be securely held at a particular position along cylindrical member 40, or when loosened, to be moved along tubular member 40 and secured again as desired. Collar 42 has a pin 44 extending downwardly therefrom. Pin 44 is representative of an initial adjustment member that is used to force spindle body 22 to approximately the central portion of ring 32 of traverse rail 30. Hence with the spindle support assembly 15 slightly loosened to the point where spindle 20 may be moved laterally, pin 44 is brought to reside within the internal diameter 32' of ring 32 and may rotate therearound. As pin 44 is rotated around the internal diameter 32' of ring 32, spindle 20 is moved toward the central location within the ring 32. The accuracy of movement of spindle 20 by collar 42 and pin 44 is dependent upon the accuracy of placement of pin 44. It should further be pointed out that a plurality of pins 44 can be provided around the circumference of collar 42 or that other structural members can be provided so long as they perform the intended function. From an accuracy standpoint, it is preferable to initially bring spindle 20 into the center of ring 32 within an accuracy of only a few thousandths of an inch, say for example, 0.012 inch.

A second collar or clamp 46 is also provided around cylindrical member 40 and is provided with a bolt 47 or the like so as to render collar 46 adjustable along the length of tubular member 40 in the same manner as discussed with respect to collar 42. Collar 46 has a mount 48 associated therewith and extending outwardly from one side thereof. A swivel joint 50 is provided on mount 48 and receives a rod 51 therethrough. Rod 51 is adjustable with respect to swivel joint 50 so as to be moved up or down therethrough while retaining the ability to swivel therewith. A dial indicator 60 is received at the end of rod 51 opposite swivel joint 50. Dial indicator 60 is attached to rod 51 by further swivel joint 53.

Referring to FIGS. 1 and 2, the dial indicator 60 is comprised of a base 61 having a feeler 62 pivotally

secured at one end thereof. A dial face 63 is presented at an opposite end of base 61 having indicia 64 therearound. An indicator 65 is operatively associated with feeler 62 and depending upon a displacement of feeler 62, will deviate from its normal position around dial face 63 to provide a reading, indicated by indicia 64 that is proportional to the deflection of feeler 62.

Once spindle 20 has thus been moved to the approximate center of ring 32 of traverse rail 30, collar 46 may be moved into position such that feeler 62 can be rotated around the internal diameter of ring 32 or the outer diameter of ring 32 to indicate both the amount of deviation that spindle 20 is from the exact center of ring 32 and also the location of the deviation. Having noted the deviation on indicator 60, the spindle is tapped in the appropriate direction to be placed in the exact center of ring 32.

In some cases, to maintain spindle 20 at the exact center of ring 32, it is necessary to shim spindle 20 in a particular direction. The shimming is accomplished by the use of a precision paper or the like to achieve the desired positioning of spindle 20. After spindle 20 has been appropriately located both perpendicular to traverse rail 30 and within the center of ring 32, the spindle support system 15 is again tightened against spindle rail 10 and the spindle then remains in its new adjustment.

The spindle plumbing device as shown in FIG. 1 is ideally suited for plumbing a spindle when the spindle is idle. It is oftentimes felt desirable to adjust the plumb of the spindle when the spindle is rotating which would, of course, more closely duplicate operating conditions of the apparatus when receiving yarn on a package supported thereon. As such, a further embodiment of the present invention is shown in FIG. 3 which may be used to plumb a spindle either when idle or when rotating. In many respects, the embodiment of the present invention as shown in FIG. 3 is quite similar to the embodiment shown in FIG. 1 and numbers will be preceded by a 100 suffix for corresponding parts.

FIG. 3 illustrates a spindle 120 that, though not shown, could be similarly supported in the manner as shown in FIG. 1. The spindle 120 has an elongated spindle body 122 which, as was mentioned with respect to FIG. 1, normally receives a textile carrier therearound on which yarn is deposited in a uniform manner. An elongated tubular member 140 having a longitudinal bore 141 therein is positioned around spindle body 122. Bore 141 of elongated cylindrical member 140 has a bearing surface received therein, represented by two bearings 170. Bearings 170 are secured to tubular member 140 and are disposed along the length of bore 141. Referring to FIG. 4, a bearing 170 is shown to have a central spindle engaging sleeve or race 171 which is separated from bearing 170 by a plurality of roller elements 172. Roller elements 172 may be roller bearings, ball bearings, pin bearings, or the like. If necessary, thrust bearings or the like may be used to secure race 171 in place.

As shown in FIGS. 3 and 4, the spindle body 122 resides snugly within sleeve 171 of bearing 170. As such, as spindle 120 rotates, the spindle body 122 likewise rotates along with sleeve 171 around the roller elements 172 while the elongated element 140 is held stationary. The bearing surface of the embodiment

shown in FIGS. 3 and 4 thus permits the device to be utilized on a spindle while the spindle is rotating and as such, to plumb the spindle under conditions most closely approximating the actual operating conditions where yarn is being applied onto a carrier supported by the spindle. Though two bearings 170 are shown to reside within bore 141 of elongated element 140, a single bearing surface could likewise be provided, the tubular element 171 of which would conform to the shape of the spindle body to snugly receive same for rotation therewith. Likewise, depending upon the desires of an individual, any number of bearings could be provided to realize the end result.

Elongated cylindrical member 140 has attached to an outer side thereof an adjustable stop member 180. Stop member 180 preferably is threaded to be screwed into the side of elongated member 140 and is comprised of a plurality of telescoping sections 181, 182 and 183. Stop member 180 may thus be extended outwardly from the device of the present invention to the next adjacent spindle (not shown) when used to plumb a rotating spindle such that, the plumbing device is held against rotation while the spindle 120 rotates therein. A pivotal connection between member 140 and stop member 180 may be desirable which would permit stop member 180 to be moved for engagement with elements other than an adjacent spindle.

Elongated cylindrical member 140 may further be provided with a spirit level 190 in the upper end thereof. Spirit level 190 is secured to elongated member 140 and, referring to FIG. 5 is seen to have a clear upper surface with a circle 191 inscribed thereon. Spirit level 190 is filled partially with a fluid while leaving an air bubble therein. Hence if a spindle plumb is to be checked after alignment with the device of the present invention, a quick glance at the top of the cylindrical member 140 will indicate whether the spindle is plumb. If the spindle is plumb, the air bubble 192 will reside in the center of circle 191 that is inscribed on the top of spirit level 190. This feature of the device of the present invention is optional and may be used with the embodiment shown in FIG. 1 or FIG. 3 as desired.

The embodiment of the present invention when used for plumbing rotating spindles has a further feature that may be advantageously employed. Referring to FIG. 3, collars 142 and 146 are shown to each have a bearing surface 142' and 146' respectively against elongated cylindrical member 140, and retainer rings R and R' respectively thereunder. Thus collars 142 and 146 retain their vertical adjustment capability with respect to member 140 and after being properly positioned, are held thereat by retainer rings R and R'. The bearing surfaces 142' and 146' then permit collars 142 and 146 to rotate around member 140. Hence when the device of the present invention is used to plumb a rotating spindle, spindle 120 rotates while member 140 is held against rotation by adjustable stop 180. Collars 142 and 146 when equipped with bearing surfaces 142' and 146' may also be rotated during plumbing operation. This feature improves the efficiency of plumbing since adjustable stop 180 does not have to be moved to rotate the entire device. Further, the bearing equipped collars 142 and 146 may also be employed with the device as shown in FIG. 1.

The remaining features of the device as shown in FIG. 3 are like those as described with respect to FIG. 1. As such, further elaboration as to these parts of the device of the present invention will not be made.

Using the device as illustrated in FIG. 3, a spindle 120 may be plumbed by loosening the appropriate apparatus, placing the elongated member 140 over the spindle body 122 where the body 122 resides snugly within bearings 170 and then bringing the first collar 142 into position to initially adjust the attitude of spindle 120. Thereafter, the indicator 160 is appropriately used and rotated on bearing 146' around the ring 132 of traverse rail 130 to indicate whether the spindle 120 is disposed without the center of ring 132, and if so, the amount of deviation and also the direction of deviation.

Though the Figures show two adjustable collars around the elongated member of the device, one adjustable collar could be provided having the initial spindle adjustment means and the dial indicator provided thereon. Moreover, though the dial indicator of the type shown in the Figures as preferred, obviously other types of indicators could be provided to achieve the equal result.

Having described the present invention in detail, it is obvious that one skilled in the art will be able to make variations and modifications thereto without departing from the scope of the invention. Accordingly, the scope of the present invention should be determined only by the claims appended hereto.

What is claimed is:

1. A spindle plumbing device for a textile machine, wherein said textile machine has a rail that traverses the spindle lengthwise to distribute yarn along the length of the spindle and supports a ring around each spindle, said plumbing device comprising:

- a. an elongated member having a longitudinal bore therein, said member being adapted to reside over said spindle;
- b. a vertically adjustable collar received around said elongated member, said collar having initial spindle adjustment means thereon; and
- c. an adjustable indicator means associated with said elongated member for vertical and horizontal adjustment with respect thereto, said indicator means being movable around said elongated member to determine whether said spindle is properly positioned with respect to said rail.

2. A spindle plumbing device as defined in claim 1 wherein said indicator means is a dial indicator having a pivotal feeler engageable with said ring around said spindle and wherein said dial indicator is associated with a second vertically adjustable collar, said collar

being positioned around said elongated member.

3. A spindle plumbing device as defined in claim 1 wherein a bearing surface is received within said longitudinal bore of said elongated member, said bearing surface being engageable with said spindle during plumbing and permitting said spindle to rotate during plumbing.

4. A spindle plumbing device as defined in claim 3 wherein said bearing surface is comprised of a plurality of separate bearings, each bearing being rigidly secured to said elongated member.

5. A spindle plumbing device as defined in claim 1 comprising further a spirit level received in the top of said elongated member.

6. A spindle plumbing device as defined in claim 3 comprising further rotational prevention means secured to said elongated member and extending outwardly therefrom.

7. A spindle plumbing device as defined in claim 6 wherein said rotational prevention means is comprised of a plurality of members, each being telescopingly associated with the next adjacent member.

8. A spindle plumbing device as defined in claim 1 wherein said initial spindle adjustment means comprises at least one pin type member secured to said collar and extending axially outwardly therefrom.

9. A spindle plumbing device as defined in claim 4 wherein a spirit level is received in the top of said elongated member.

10. A spindle plumbing device as defined in claim 1 wherein a bearing surface is received within said longitudinal bore of said elongated member to rotatably receive a spindle, said initial spindle adjustment means comprises at least one pin secured to said collar and extending axially outwardly therefrom, said indicator means is pivotally received on a second vertically adjustable collar around said elongated member and a spirit level is received in the top of said elongated member.

11. A spindle plumbing device as defined in claim 10 wherein said indicator means is a dial indicator having a pivotal feeler engageable with said ring around said spindle.

12. A spindle plumbing device as defined in claim 3 wherein said collar is provided with a bearing surface to permit rotation thereon with respect to said elongated member.

13. A spindle plumbing device as defined in claim 10 wherein said collars are provided with a bearing surface to permit rotation thereon with respect to said elongated member.
